UNITED STATES PATENT OFFICE

ALBERT J. HORTON, OF WHITE PLAINS, NEW YORK, ASSIGNOR TO R. HOE & CO., INC.,
OF NEW YORK, N. Y., A CORPORATION OF NEW YORK

WEB ROLL CHANGER

Application filed July 16, 1927. Serial No. 206,209.

This invention relates to certain improvements in web roll controlling and web roll changing and pasting mechanism for printing machines.

5 In modern high speed press operation, the web rolls have to be renewed from time to time during the press run. In the operation of these printing machines saving of time is, of course, of the highest importance and it is 10 desirable that the operation of the press shall be interfered with to the least possible degree during this web renewal.

It is the especial object of the present invention to design a roll changing and pasting mechanism for web presses in which there is provided a rotary support for supporting a running web roll and a spare web roll which is automatically rotated to bring a spare roll into a position in which it is pasted or spliced 20 to a web from the expiring roll and the expiring web severed, the support then continuing its movement to a running position, the movement of the support to the running position bringing the support into position for 25 a new spare roll to be loaded therein, this cycle of operations thus comprising a complete rotation of the roll support, the movements of the support being entirely automatic.

30 It is the further object of the invention to provide a web roll changing mechanism in which a movable support is employed for supporting a running web roll and a spare web roll which will automatically move from a loading position to a position at which a new web roll may be pasted or spliced to an expiring web and then moved to running position, and after the web has nearly expired and has been pasted to the fresh roll the support is moved to a loading position and the new roll to running position, this cycle of 40 movements being entirely automatic and controlled only by the expiring roll when such expiring roll has been reduced to a predetermined diameter, the arrangement being such

that the mechanism operates only at the desired point on the expiration of the roll, so that variations in the position to which the support may be moved is immaterial and does not affect the operation of the mechanism. 50

A further object of the invention is to provide an improved construction of simple form for effecting these desired objects.

With these and other objects not specifically referred to in view, the invention consists in certain novel parts, arrangements and combinations which will be described in connection with the accompanying drawings and the novel features pointed out in the claims hereunto annexed. 55

In these drawings,—

Figure 1 is an end elevation showing the parts in normal running position with a web from a full roll feeding into the press and a reserve roll just having been placed in position; 65

Figure 2 shows the position of the parts with the support rotated so that the reserve roll is about to be pasted or spliced to the web running from the expiring roll; 70

Figure 3 shows the position of the parts with the support rotated further in a clockwise direction and the reserve roll pasted or united to the old web, and the latter being severed from the spent roll; 75

Figure 4 shows how the support may be operated to remove a full or a running roll if it is desired to remove it from the mechanism for any purpose; 80

Figure 5 is an end view, partly broken away and partly in section, of the mechanism shown in Figure 1, looking in the direction of arrow 5 of that figure, and

Figure 6 is a plan or top view of the construction shown in Figure 1, looking in the direction of arrow 6 of that figure, certain parts being broken away and certain parts being omitted. 85

Referring now to the drawings, the ma- 90

chine chosen to illustrate the invention includes a rotary support arranged to support a running roll and a spare roll, this support during a complete rotation moving from loading position to a position where a new roll may be pasted to a web from the expiring roll, then to a normal running position under control of certain friction means and also to loading position, this cycle of movement being entirely automatic and controlled entirely by the decrease in size of the running roll. It will be understood, however, that as to certain features the invention is applicable to other forms of movable roll supports and is not to be restricted to a support having a complete rotary movement.

Referring to the construction illustrated, however, there is provided side frames 1, 2 on which are mounted a pair of brackets 3, 4 in which is journaled a rotary shaft 5. This shaft 5 is given a rotary movement through a motor and suitable gear connections, not shown, as these are well understood in the art. Mounted on this shaft are a pair of arms 6, 7, in the opposite ends of which are bearings 8, 9 for rotatably supporting a running web roll R and a spare web roll S, the web rolls being loaded into the arms when the parts are in the position shown in Figure 1, from a truck 10, or in any other suitable manner.

In accordance with the invention, means are provided for effecting an automatic rotation of the arms to effect their movement to pasting, running and loading position, and in the preferred form of the invention this movement will be controlled entirely by the expiring roll when it has been reduced to a predetermined diameter. Means are also provided for severing the expiring web after the paste, for bringing the new or reserve roll up to web speed at the time the paste is made, and for controlling the tension of the running web.

While these various agencies may vary somewhat in construction, in the machine shown, referring to Figures 1 and 5, the tension on the running roll is controlled and maintained by friction means, shown in the form of narrow straps or belts, marked 11, three such belts being shown. These straps or belts are each secured at one end to arms 12 pivoted on a cross shaft 13 supported in bearings in brackets 14 secured to the frames 1, 2, before referred to. These straps or belts are arranged to pass around and engage about one half of the surface of the running roll, and have adjustable weights 15 secured to their free ends.

The belts or straps pass over pulleys 16, loose on a shaft 17, suitably journaled in brackets 17' depending from side frames 18, 19 of the press (see Figure 6) and over a guide roll 20 supported in brackets 21, one of which is shown, the guide roll 20 being arranged beyond the pulleys 16, so that the free

ends of the straps are clear of the running roll in its various positions. These belts or straps serve to maintain pressure against the web roll surface and maintain the desired web tension during the unwinding of the roll.

Constructions embodying the invention will include means for automatically rotating the web roll supporting arms when the running roll reaches a predetermined diameter, and these means preferably will be such as to function regardless of the position at which the web roll support stops when moved to the running position shown in Figure 1.

While the specific construction of these means may vary, as shown, there is provided a long controller arm 22 and a short arm 23, both these arms being fast on the shaft 17, before referred to. The long arm 22 engages the unwinding roll, and while if desired the arm may contact directly with the roll surface, preferably, as shown, it is arranged to bear against one of the straps or belts, as for instance the center, the arm 22 being provided with a bend 24 (Figure 5) so that it will clear the belt pulley.

The arm 22 resting on the strap or belt, which in turn bears on the surface of the web roll, follows the roll as it decreases in size, rocks the shaft 17 and shifts the position of the short arm 23.

This short arm 23 is arranged to actuate a switch which starts the motor operating the roll support. While this may be done in various ways, in the preferred construction means will be provided by which only a predetermined diameter of the expiring web roll will cause the starting of the motor. As shown, there is a second controller arm 25 provided with a controller switch 26, having a push button 27 which closes a circuit indicated at a-b (Figure 1) for the operating motor. The controller arm 25 is loose on the shaft 17 and bears against a boss 28 of one of the roll supporting arms, as the arm 6, this boss being concentric with the core 29 of the web roll supported in the arms 6, 7, one of these bosses being provided at each web roll position on the arm.

From the construction so far described it will be seen that as the running web roll decreases to a predetermined diameter the arm 22 brings the arm 23 into contact with the push button 27, operates the switch and starts the motor, and by adjusting the position of the arm 23 on the shaft 17 this action will occur at any desired diameter of the web roll. Furthermore, this is independent of any variation of the position of the web roll support, owing to the controller arm running on the concentric boss 28, such variation being compensated for by the automatic shifting or changing of the arm 25 and with it the switch 26. A stop 30 may be provided with which cooperates a pin 31 carried on the

frame 19 (see Figures 5-6), to prevent undesired rearward movement of the arm.

As the motor starts, the web roll support is rotated clockwise to the position shown in Figure 2. Machines embodying the invention will include means for speeding up the new roll S to the speed of the running web, and these means are preferably driven from the press. Various devices may be employed for this, but in the construction shown there are provided a plurality of rolls 32 (Figure 6) on a shaft 33 supported in a pair of arms 34, 35 pivoted on a shaft 36 journaled in the side frames 18, 19, before referred to. This shaft 36 is driven from a shaft 37 geared to the press, through a gear 38 on the shaft, intermediate gear 39, and gear 40 on shaft 36, shaft 33 being driven from shaft 36 by a chain 41. If desired, a stop 42 may be provided on the arm 34 cooperating with a pin 43 fast in the machine frame to prevent the arms 34, 35 from dropping downwardly so far as to interfere with the movement of the spare roll S into position.

Construction embodying the invention will include means for severing the expiring web and for stopping the rotation of the expired roll, though this latter means is unnecessary to the operation of the machine and may be omitted if desired. The specific construction of these means may be varied, of course, but in the best constructions the severing means will be operated with a quick action so as to insure complete and quick severance of the web. As illustrated, the shaft 13 is provided at one end outside the arms 12 with a short arm 44 which is connected by a link 45 to an arm 46 fast on a rock shaft 47 journaled in brackets 48, 49 secured to the frames 1, 2, before referred to. This shaft 47 has fast thereon arms 50, 51 which support a cross-member or bar 57 on which is mounted the web severing device, shown as a serrated cutting knife 52. Also secured on the shaft 47 is an arm 53 to which is connected one end of a spring rod construction 54 which tends to keep the parts in the position shown in Figure 1. If desired, brake plungers 55 may be provided which engage the surface of the expired roll to stop its rotation after the running or old web has been severed. These plungers are resiliently mounted and have shanks 56 extending through the bar 57 by which they are secured in position by the usual locknuts.

As the web roll support turns from the position shown in Figure 2, the spare roll S is brought up to web speed by the friction rollers 32, it being understood, of course that adhesive has been applied to the surface of the spare roll. As the rack is thus turned, the running roll presses against the arms 12 and forces them into the position shown in Figure 2, thus putting the spring 54 under compression. A further movement of the roll supporting arms to the position shown

in Figure 3 brings the spare roll into contact with the web running from the expiring roll and the paste is made, the end of the new or spare roll following the old web into the press. The old roll, having moved past the ends of the arms 12, releases the arms and these arms move upward out of the way, and at the same time the spring operates the cutting knife 52 which severs the old web, and by the same movement the brake shoes 55, where these are employed, come into contact with the surface of the expiring roll and stop it. The rotation of the roll supporting arms is continued until the parts have again reached the normal running position, that is, the position shown in Figure 1. The expiring roll may then be removed and a new roll readily put into position. It will be observed that the arrangement of the belts or straps acts to maintain the desired amount of wrap on the roll while it is running, and the mechanism for cutting off the expiring web is a very quick one, so that a full severance of the web is effected.

When the new roll has reached the running position, the motor is automatically stopped by means of a limit-switch, indicated at 60, this switch being operated by projections 61 turning with one of the roll supporting arms, as the arm 6. It is understood that the switch 60 is connected electrically in parallel with the switch 26 and in series with the motor and it will be further understood that when either switch is closed the motor will operate to turn the web roll support as described. In the operation of the mechanism both switches are open while the running roll is unwinding. When, however, the running roll has been reduced to a predetermined diameter the contacts of switch 26 are closed, thereby starting the motor and as the support rotates the contacts of switch 60 are closed when disengaged from one of the projections 61. The support will then continue to turn until the opposite projection again engages and operates the switch 60 to open the circuit, the switch 26 in the meantime having been opened by the positioning of the new roll.

Under certain circumstances it may be desirable to remove the running roll from its roll supporting arms before it has been exhausted, as for instance in changing from a full length roll to a shorter one. Where this is desired, the roll support can be independently turned, under manual control, by suitable switch arrangements, which are not shown as they are well understood in the art, the arms 12 being so arranged as to permit a roll to be moved past them, the arrangement of the parts for permitting this to be done being shown in Figure 4.

While the invention has been shown and described in its preferred form, it will be

understood that various changes may be made in the specific construction and arrangement of the parts without departing from the invention as defined in the appended claims.

5. What I claim is:

1. In a web roll controlling mechanism, the combination of a rotary support capacitated to carry a running web roll and a spare web roll, friction means engaging the surface 10 of the running web roll to control it while unwinding, and means controlled by the running roll for automatically rotating the support to bring the spare web roll from loading position to pasting position, running position and again to loading position.
- 15 2. In a web roll controlling mechanism, the combination of a movable support capacitated to carry a running web roll and a spare web roll, friction means engaging the surface of the running web roll to control it while unwinding, and means controlled solely by the diameter of the running web roll for automatically moving the support to bring the spare web roll into pasting and running positions.
- 20 3. In a web roll controlling mechanism, the combination of a movable support capacitated to carry a running web roll and a spare web roll, and means controlled solely by the 30 diameter of the running web roll for automatically moving the support to bring the spare web roll into pasting and running positions.
- 35 4. In a web roll controlling mechanism, the combination of a rotary support capacitated to carry a running web roll and a spare web roll, friction means engaging the surface of the running web roll to control it while unwinding, means controlled by the 40 running roll for automatically rotating the support to bring the spare web roll into pasting and running positions, and means for severing the expiring web after the paste has been made.
- 45 5. In a web roll controlling mechanism, the combination of a movable web roll support capacitated to support a plurality of web rolls, and means controlled solely by the 50 diameter of a running web roll for automatically moving the web roll support successively from running to pasting and to running and loading positions.
- 55 6. In a web roll controlling mechanism, the combination of a movable support capacitated to carry a running web roll and a spare web roll, means controlled solely by the diameter of the running web roll for automatically moving the support to bring the spare web roll into pasting and running positions, 60 and means controlled by the movement of the support for severing the expiring web after the paste has been made.
- 65 7. In a web roll controlling mechanism, the combination of a movable support capacitated to carry a running web roll and a spare

70 web roll, means controlled solely by the diameter of the running web roll for automatically moving the support to bring the spare web roll into pasting and running positions, means controlled by the movement of the support for severing the expiring web after the paste has been made, and means for bringing the spare web roll up to web speed prior to making the paste.

75 8. In a web roll controlling mechanism, the combination of a movable support capacitated to carry a running web roll and a spare web roll, a controller arm following the running web roll as it decreases in size, a second controller arm engaging the support, and a switch controlling the movement of the support, said switch being actuated when the arms come into a predetermined relation with each other.

80 9. In a web roll controlling mechanism, the combination of a movable support capacitated to carry a running web roll and a spare web roll, a controller arm following the running web roll as it decreases in size, a second pivoted controller arm engaging the support, and a switch controlling the movement of the support carried by the second arm and moving therewith, said switch being actuated when the arms come into a predetermined relation with each other.

85 10. In a web roll controlling mechanism, the combination of a movable support capacitated to carry a running web roll and a spare web roll, a friction belt or strap engaging the surface of the roll and following the roll as it decreases in size, a controller arm engaging the strap, a second controller arm engaging the support, a switch controlling the movement of the support carried by the second arm, and means for actuating the switch when the arms come into a predetermined relation with each other.

90 11. In a web roll controlling mechanism, the combination of a movable support for supporting a running web roll and a spare web roll, a friction belt or strap engaging the roll surface to control it while unwinding, a pivoted arm to which one end of the belt or strap is secured, said arm being moved by a movement of the support, means for severing an expiring web, and means actuated by the movement of the arm for putting the web severing means under tension so that such means will act with a quick movement for web severing.

95 12. In a web roll joining mechanism, the combination of means for pasting a new web roll to an expiring web including a movable support, and spring controlled means tensioned through the movement of the support for severing the old web after the paste.

100 13. In a web roll controlling mechanism, the combination of means for pasting a new web roll to an expiring web including a movable support, friction means for controlling

the expiring web, means for severing an expiring web, and spring means connected with the friction means for actuating the severing means.

5. 14. In a web roll controlling mechanism, the combination of means for pasting a new web roll to an expiring web including a movable support, a friction belt or strap engaging the web, a pivoted arm to which 10 one end of the belt or strap is secured, a severing knife, an arm carrying the knife, a spring connected with the knife arm, and connections between the arms.

In testimony whereof, I have hereunto set
15 my hand.

ALBERT J. HORTON.
